(57) **CLAIM**

The ornamental design of a combined beverage container holder and mounting ring, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyrights whatsoever.

FIG. 1 is an elevated view, showing the beverage container placed in the mounting ring, and, in dashed lines, a representative container, such as a cup.

FIG. 2 is a side view, showing the beverage container placed in the mounting ring, details of two of the fasteners, and, in dashed lines, a support platform attached to the mounting ring.

FIG. 3 is a rear view, showing the beverage container placed in the mounting ring and details of two of the fasteners.

FIG. 4 is a front view, showing the beverage container placed in the mounting ring and details of three of the fasteners.

FIG. 5 is an elevated view of the underside of the beverage container placed in the mounting ring, showing the bottom of the beverage container and mounting ring

FIG. 6 is a direct overhead view of the beverage container holder, looking down into the beverage container.

FIG. 7 is a direct overhead view of the underside of the beverage container placed in the mounting ring.

FIG. 8 is an elevated view of the mounting ring.

FIG. 9 is a direct overhead view of the mounting ring

FIG. 10 is a direct overhead view of the underside of the mounting ring.

FIG. 11 is a side view of the mounting ring.

FIG. 12 is a front view of the mounting ring.

FIG. 13 is a front view of the mounting ring.

FIG. 14 is an elevated view of the beverage container.

FIG. 15 is a side view of the beverage container.

FIG. 16 is rear view of the beverage container.

FIG. 17 is front view of the beverage container.

FIG. 18 is a direct overhead view into the inside of the beverage container; and,

FIG. 19 is a direct overhead view onto the bottom of the beverage container

The broken lines showing a cup are for illustrative purposes only and form no part of the claimed design.

The beverage container holder and mounting ring are shown separately for clarity of illustration.

1 Claim, 10 Drawing Sheets .
